UNITED STATES PATENT OFFICE.

LOUIS LÉON LE FRANC, OF BOSC-LE-HARD, FRANCE.

MANUFACTURE OF WOODEN STOPPERS.

SPECIFICATION forming part of Letters Patent No. 663,234, dated December 4, 1900.

Application filed December 28, 1898. Serial No. 700,495. (No specimens.)

To all whom it may concern:

Be it known that I, LOUIS LÉON LE FRANC, a citizen of the Republic of France, and a resident of Bosc-le-Hard, in the Republic of France, have invented a new and useful Improvement in the Manufacture of Wooden Stoppers, which is fully set forth in the following specification.

The experience gained in previous researches respecting the application of wood for corking liquids has convinced me that the methods which I have followed hitherto to render wood supple and impermeable presented difficulties which rendered said system of corking too complicated. I therefore began experiments with a view of avoiding said difficulties and succeeded in doing so by discovering a new method of treatment and preparation of wood. These new methods govern my invention according to the present application for patent.

In the treatment of wood for the purpose of rendering it supple I used in the past acids for destroying to a certain extent the incrustating substances and the cellulose or alkaline solutions for eliminating completely or partially the incrustating substances. I have since found that both these means present a serious drawback. Both produce in the fiber of the wood such modifications that the wood contracts when being dried, said contraction being sometimes very considerable.

A more thorough study of the wood fiber has convinced me that the chemical composition of the incrustating substances which give wood its greater or less strength is practically analogous to that of glucosides and that consequently said incrustating substances could be removed by oxidation. I therefore pursued my experiments as to treatment of wood in this direction, and thus succeeded by oxidizing it in imparting to it remarkable qualities of suppleness by suitable elimination of the incrustating substance without rendering it liable to contraction or shrinkage.

The process of treatment of wood by oxidation may be divided into two processes—one the treatment of hard wood—*i. e.*, of wood with a large proportion of incrustating matter—and the other of soft wood when such is used—such as, for instance, poplar, in which the proportion of incrustating matter is com-

paratively small. However, by varying the strength of reagents used either of these processes may be used, whatever be the nature of the wood employed. In fact, the choice to be made is determined only by experience. I may also oxidize the incrustating substances by any well-known oxidizing agents—metallic, alkaline, or earth-alkaline oxids, or peroxids, bichromates, iodates, manganates, permanganates, sulfates, nitrates, chlorates, and alkaline or metal chlorids, or chromic, manganese, hydrochloric, chloro-chromic, nitric, &c., acids. All these compounds are employed at a strength determined by requirements. In these conditions it is possible to attain the desired results; but, as already mentioned, I prefer to use one of the following methods, according to the particular case.

Processes of treating wood.—First. For hard or semihard wood or when an exceptional suppleness is to be obtained. In such cases I use nitric acid mixed with a chlorin derivative—such, for instance, as a soluble chlorate. This addition of chlorin not only has an oxidizing effect, but also prevents the wood from becoming colored by the treatment. I dilute the nitric acid mixed with an alkaline chlorate to an extent varying with the nature of wood to be treated and determined experimentally, the point at which no more nitric-acid fumes are formed being observed as a limit. As a rule the solution consists of one hundred parts of commercial nitric acid at 36° Baumé and one hundred parts of water containing twenty parts of chlorate of potash or soda. The wood to be treated is placed in a closed vessel, constructed to withstand the action of the acid solution, either in blocks of a cross-section of, say, thirty millimeters square and of any length, or in the shape of cylinders or rods of the size of the corks or stoppers, or, which is preferable, in cylinders inwardly recessed, so as to reduce the proportion of liquid absorbed by the wood. When the receptacle is filled with wood to about three-fourths of its volume, the acid solution is introduced into it by suction. In order to accelerate the process of impregnation, the pressure in the apparatus is either reduced or increased. The material remains in contact as long as necessary, the period of the treatment varying with the kind of wood.

treated. It is preferable to find the correct time experimentally; but as a general rule the materials may remain in contact for from four to six hours at a temperature from 25° to 30° centigrade. When the oxidizing action has sufficiently modified the incrustating substances, the nitric solution is drained off and immediately replaced by cold water. Lixiviation by a current of water is continued 10 until the perfect neutrality is attained and the last traces of the reagent have disappeared. This lixiviation is advantageously assisted by an increase or reduction of pressure or by the use of hot water toward the 15 end of the operation. The solution used for the treatment may be employed again, provided that it is renewed or strengthened as it becomes exhausted. The wood thus prepared is thoroughly dried and submitted to a 20 process for rendering it impermeable, which will be hereinafter described.

Second. Soft wood, more easy to render supple. In this case I preferably employ hydrochloric acid with an alkaline chlorate. This 25 method may be also, as already stated, applied to the treatment of hard wood, in which case it is simply necessary to use stronger solutions. In case of a soft wood to be treated—such, for instance, as poplar—the process is 30 as follows: A solution of one hundred kilograms of water and five kilograms of chlorate of potash or soda is prepared in an open leaden or even copper vessel provided with a heating device. The solution is boiled and 35 the wood is immersed as in the first case, preferably, however, in the shape of cylinders of the same size as the corks or, still better, in the shape of such cylinders internally recessed for the purpose of facilitating subsequent lixiviation. The whole is boiled until the wood is completely saturated with the 40 chlorated water. When this point is reached, a quantity of commercial hydrochloric acid equal to that of the alkaline chlorate is added 45 to the vessel and the boiling continued until the alkaline chlorate is completely decomposed. This operation is slow, and it takes from three to four hours to arrive at a regular oxidation. The oxidation having thus 50 been effected, the acid solution is discharged and replaced by hot water, which is caused to circulate and is renewed until the reagents have been eliminated. Cold water may also be used, in which case the wood is left in it 55 for several days. This wood, freed from all foreign matter, is thoroughly dried and submitted to the operation for rendering it impermeable.

Whichever of these methods be used whenever I proceed by oxidation I obtain wood, which after being immersed into hot, lukewarm, or cold water becomes as supple and as elastic as cork.

I mentioned in the beginning of this description that the methods according to which I operated to render wood impermeable and air and water tight present certain difficulties

in the application to corking with wood. In effect, owing to its texture, wood, unlike cork, can be used for corking purposes only in the 70 direction of its longitudinal fibers, as its transverse fibers are not strong enough. It follows that, owing to capillary action, it cannot be impermeable. In order to render it impermeable, it is necessary to be able if not to 75 stop or clog its longitudinal texture throughout the whole of its length at least to intercept it to a sufficient extent to prevent the passage of liquids or gases. I found that if the introduction into the texture of wood of 80 a substance which renders it impermeable is effected by the method I used before it is possible to render it impermeable; but then it presents serious drawbacks from a practical point of view. In fact, if a stopper is 85 immersed in a solution for rendering it impermeable and said solution is caused by pressure or vacuum to penetrate into its tissues in all directions—that is to say, both transversely and longitudinally of the fibers—the 90 wood loses all its suppleness, becomes hard, rigid, and nearly incompressible. Moreover, if by exercising a powerful pressure it is compressed so as to reduce its cross-section, which is one of the requirements of corking, the 95 greater portion of the substance which renders it impermeable will be pressed out. One is therefore face to face with the following drawbacks: The stopper having lost its elasticity requires a powerful pressure in order 100 to introduce it into the neck of the bottle, which it fits in a very imperfect manner owing to the same cause. The compression forces out a portion of the substance, which, though 105 it may be harmless, becomes mixed with the liquid in the bottle, and finally the expulsion of said substance from the fiber removes the guarantee of impermeability of the stopper.

From the preceding and in order to allow of successful corking it follows that the first 110 thing to be obtained is the impermeability of the long fiber, as it alone can let liquids or gases pass, the short or transverse fibers not being able to let any liquid through, as their ends are effectually closed by the contact 115 with the neck of the bottle. This consideration underlies my new process, which is carried out in the following manner: The stoppers having been rendered supple and lixiviated are dried to such an extent as to contain enough moisture to remain supple, or if 120 it is desired to operate in a more constant manner they are thoroughly dried and afterward dipped into boiling water or submitted to the action of exhaust-steam until they have 125 acquired the desired elasticity. The stoppers are then impregnated in accordance with my process, an apparatus such as shown in the drawings being employed.

In the drawings, Figure 1 is a plan view of 130 a tray or plate on which the stoppers are placed, and Fig 1^a is a longitudinal section thereof. In both of these figures the central portion is not completed, and it will be un-

derstood that it will appear like the end portions. Fig. 2 is a transverse section of the boiler or vessel in which the said trays or plates filled with stoppers are placed; and 5 Fig. 3 is an end elevation of the same, partly broken away.

P indicates a plate or tray, which is provided with a large number of holes *t*, arranged in parallel rows. The holes *t* are 10 slightly conical and have a diameter at their upper part which is from two to four millimeters greater than that of the stoppers, while at their lower part they have a diameter at least a millimeter less. The thickness of 15 the tray or plate is greater than the length of the stoppers. The difference in diameter has for its object to produce a slight contraction of the stopper, so that it will snugly fit into the hole *t*. Only the upper and lower ends 20 of the stoppers will be in contact with the impregnating substance, the sides being entirely inclosed. When the stoppers are to be placed in position, they are softened by boiling water or steam and are then pressed into 25 the holes *t t* by means of a machine similar to that for corking bottles. When the plate or tray is filled with stoppers, it is placed into a boiler or vessel D, which is of cylindrical shape, of sheet metal, and is opened 30 or closed by means of a door *n*, which is sustained by a suitable support K. The vessel D is provided with an interior heating-coil D' or other suitable source of heat, the temperature of which is regulated by a thermometer which is located in one side of the 35 vessel. Extending transversely across the vessel D is a series of shelves formed of bars R. Onto these shelves the trays or plates filled with stoppers to be treated are placed. 40 The vessel may contain eleven to twelve trays or plates containing each three hundred stoppers, so that from three thousand three hundred to three thousand six hundred stoppers can be treated at one operation.

45 For treating the stoppers by means of paraffin, for example, the operation is as follows: The vessel or boiler being hermetically closed is charged with trays or plates containing stoppers. Through a pipe C a partial 50 vacuum is produced in the vessel by means of a suction-pump, while the liquid paraffin is drawn into the vessel through pipe A. When the trays or plates are immersed in the paraffin, the temperature is raised to 80° or 55 90°, while a vacuum tension of from fifty-five to sixty centimeters of mercury is produced, and under these conditions the water is evaporated and is replaced by the paraffin.

It is obvious that the evaporation of the water and the introduction of the paraffin 60 can take place only through the upper and lower ends of the stoppers, as the cylindrical surfaces of the stoppers are held under pressure throughout by the walls of the holes *t t*. Therefore the introducing of the impregnating 65 substance can only take place in the longitudinal direction of the fibers, which is essential, as has been fully stated already. When the stoppers have been fully impregnated, which is determined by practice, the 70 vacuum is discontinued and the air permitted to reenter through the pipe B and the paraffin permitted to run through pipe A into a suitable receptacle until it is again required for use. The door *n* is then opened and the 75 trays or plates containing the stoppers removed, so as to permit their gradual cooling. The stoppers are afterward removed from the plates, which operation can be quickly effected by hand, although it is more convenient 80 to do it by means of a machine somewhat similar to the one used for putting stoppers into the plates.

For rendering the stoppers impermeable I may use paraffin, stearine, wax, resins, gums, 85 natural rubber, or rubber obtained from oils, gutta-percha, &c., or a mixture of these substances. The following mixture gives good results: rubber from oil, twenty; colophony, thirty; stearine, ten; paraffin, forty. 90

By "rubber" or "caoutchouc" derived from oil is to be understood a substance invented by J. de Eilembourg in 1846 and which is obtained by boiling in water, which is acidulated by nitric acid, the residuum which is 95 obtained from oils subjected to a high temperature. The product is a very elastic body, soluble in ether, and can be obtained from the residuum of nut and linseed oil.

I claim—

The process of treating wooden stoppers, which consists in subjecting the wood of which the stoppers are made to the action of a solution of potassium chlorate, and afterward decomposing the salt by a solution of hydrochloric acid, the operation taking place while the solution is heated, substantially as set forth.

In testimony whereof I have signed this specification in the presence of two subscribing witnesses.

LOUIS LÉON LE FRANC.
